UNITED STATES PATENT OFFICE.

DOROTHY GAMBLE, OF NEW YORK, N. Y.

CLOTHES-LINE SUPPORT.

1,137,395.

Specification of Letters Patent. Patented Apr. 27, 1915.

Application filed June 24, 1911. Serial No. 635,166.

To all whom it may concern:

Be it known that I, DOROTHY GAMBLE, a citizen of the United States, residing at No. 601 West One Hundred and Thirty-second street, borough of Manhattan, city, county, and State of New York, have invented certain new and useful Improvements in Clothes-Line Supports; and I do hereby declare the following to be a full, clear, and exact description of the invention, such as will enable others skilled in the art to which it appertains to make and use the same.

It is customary, particularly in tenement houses in cities, to suspend a double clothes-line between a pulley fastened to the window-framing and a second pulley fastened to a suitable support in or across the area, such an arrangement permitting of hanging the clothes on one strand of the line and pulling them out progressively as the successive articles are hung.

It is the object of the present invention to provide a device whereby the pulley at the window may be swung inside the window-framing, so that the clothes may be conveniently fastened to the line without leaning out of the window, to thereby increase the facility and safety of the operation.

The invention is characterized by the employment of a swinging pulley-carrying arm so arranged that the line pull, that is the pull due to the tension of the line and the weight of the clothes, serves to hold the arm normally outside of the window, so as not to interfere with the opening and shutting thereof, the swinging arm being combined with means for temporarily holding it inside of the window-frame while the clothes are being hung.

In the accompanying drawings, a suitable embodiment of the invention is illustrated, in which the arm is pivoted in an upright support fastened by screws in a convenient position on the wooden framework of the window, but, as will at once be understood, the arm could equally well be pivoted in a horizontal support attached to the upright frame of the window, or in a vertical support attached to the horizontal window sill. In either case the arrangement would be such that the line pull holds the arm away from the window itself, to prevent blowing of the arm against the window, and there would be provided a suitable stop for holding the arm, against the line pull, in its indrawn position.

Figure 1 of the drawings shows the described embodiment of the invention fastened to the upright framing of the window, and shows also the pulley and one end of the double clothes-line. The full line portion of the figure shows the device in the outside position, and the dotted lines show it in the inside position; Fig. 2, shows the device in side elevation; and Fig. 3 shows it in plane, this figure including also in dotted lines an indication of the inside position.

The illustrated device comprises a bracket 1, which may conveniently be struck up from a metal bar, and which comprises the upright body portion with two outwardly bent flanges 2 and 3, pierced by holes for the reception of the upright pivot bar 4 of the swinging arm. The swinging arm is continued out horizontally for a suitable distance. It has been found that a horizontal length of bar of 6 or 7 inches is satisfactory for the purpose. The bar is then bent to form a pulley-receiving loop 6 continued as a vertical portion 7, at the end of which the arm is again looped and bent downwardly to form the handle 8, this handle being bent away from the horizontal portion 5 to such an extent as to permit the loop 9 of the pulley to pass over it into the pulley-retaining loop 6. The bracket 1 is fastened to the window-frame by suitable screws, indicated at 10, and has at the upper flange 2 a short upright stop 11, shown clearly in elevation in Fig. 2 and in plane in Fig. 3.

In describing the operation of the device it may be assumed that the swinging arm is in the outside position illustrated in full lines in the drawings, when it is desired to hang clothes on the line or remove them therefrom. To this end one takes hold of the handle 8 and lifts the arm sufficiently to clear the stop 11, and then turns it inwardly into the position shown in dotted lines in Figs. 1 and 3. This is sufficient to bring the pulley, and consequently the end of the clothes-line, into a convenient position within the window, where the clothes may be hung or removed, and the line manipulated as desired.

In adopting the particular embodiment of the invention illustrated and described, the desire has been to get the utmost simplicity, and to provide a structure which may be cheap to manufacture and properly manipulated even by the most ignorant. It will nevertheless be understood that the nature

of the invention is such that it may be embodied in many different forms, and that the supporting bracket may be variously placed, as above suggested.

5. What I claim is:

In a clothes line support, an arm comprising a rod having its inner end bent down and adapted for attachment at the side of the window frame so that the arm may 10 swing horizontally in or out of the window, the other end of said rod being bent down to form a hook to receive the clothes line pulley and having a reverse bend above said

hook and substantially closing the opening thereof to prevent accidental release of the pulley, the extreme end of said arm being bent down vertically and extending below said hook to form a handle whereby said arm may be swung, substantially as described.

20 In testimony whereof I affix my signature, in presence of two witnesses.

DOROTHY GAMBLE.

Witnesses:
